UNITED STATES PATENT OFFICE.

LEVY R. BOSTICK, OF NEW ORLEANS, LOUISIANA.

CAR-SIGNAL.

1,290,495.

Specification of Letters Patent.

Patented Jan. 7, 1919.

Application filed August 3, 1916. Serial No. 112,964.

To all whom it may concern:

Be it known that I, LEVY R. BOSTICK, a citizen of the United States, residing at New Orleans, in the parish of Orleans and 5 State of Louisiana, have invented certain new and useful Improvements in Car-Signals, of which the following is a specification.

This invention relates to an improvement 10 in signal devices for street cars and the object of the invention is to afford complete protection to passengers leaving the car, to prevent rear end collisions and to save loss of time through unnecessary slowing up of 15 approaching cars.

With these various objects in view the invention consists in the novel features of construction hereinafter described, pointed out in the claims and shown in the accompanying 20 drawings, in which:

Figure 1 is a side elevation of a car provided with my signal device, and partly broken away.

Fig. 2 is a diagrammatic view of the circuits, certain boxes being shown in section.

Fig. 3 is a front elevation of a car showing the location of the box thereon.

Fig. 4 is a section on the line 4-4 of Fig. 1.

Fig. 5 is a section on the line 5-5 of Fig. 4.

In the drawings 1 and 2 designate suitable boxes of wood or metal which are placed on the front and rear of the car, 35 these terms being relative, and the boxes being placed above the headlight of the car.

Each box contains a bell 3 and an electric light bulb 4 and suitable front and side openings 5 are formed in each box in 40 alinement with the bulbs, said openings having red colored panes therein. Or if desired the lamp bulb may be colored red. Within the car vestibule and in easy reach of the motorman and conductor are pivoted 45 switches 7, one at each end of the car, and adapted to close certain circuits, when brought into engagement with contact points 6.

A suitable battery 8 is placed at any convenient point in the car.

From the battery lead conductors *a* and *b*. A circuit *c* is formed by suitable wire leading from conductor *a* to one of the contacts 6, completed by the co-operating switch 6 55 thence to the lamp in box 1 and then to a bell in box 2 and back to conductor *b*

and to the battery. A circuit *d* is also provided leading from conductor *a* through the other switch, located at the rear end of the car, to the lamp in box 2, the bell in box 60 1, and back to the battery.

These circuits may be run in any desired manner so long as the desired result is obtained.

Both circuits are normally broken at the 65 switches.

It will now be obvious that if the motorman brings the switch lever 7 at his end of the car into engagement with the contact 6 the lamp 4 in box 1 will be lighted and bell 70 3 in box 2, on the rear, will ring. The light will continue to show and the bell to ring as long as the circuit *c* is left closed and current is supplied from battery 8.

This permits the motorman to have free 75 use of both hands while the signals are operating which would not be the case if ordinary push buttons were employed to close the circuit.

Should the conductor close the switch at 80 his end of the car the reverse set of signals would be given, and if both switches are closed both bells and both lights will become operative.

I am aware of the fact that bells have 85 been placed on cars to warn discharged passengers against the approach of a car from an opposite direction and on an adjacent track; and I am also aware that signal lights have been provided for cars. 90

But the sounding or displaying of a single signal, or signals at one end of a car only, do not give the full measure of protection designed to be furnished by my device.

Assuming that box 1 is at the front of the 95 car and that said car on approaching a stopping place receives a signal in the usual manner to stop to discharge passengers, the motorman seeing an approaching car on the other track moves switch lever 7 to position 100 on the contact 6. A light is displayed in box 1 at the front and the bell 3 is sounded in box 2 at the rear. The first signal, from box 1 warns the motorman of the approaching car that he is about to pass a car stopping to let passengers off. This is of course a night signal when such warning is usually necessary. The passenger is also warned by the bell at the rear end that there is an approaching car on the other track, and this 110 signal is desired at all times, day as well as night.

The motorman of the approaching car has ample time to get his car under control, and the passenger is warned against crossing.

But should no stop signal be received no 5 warning signal is given, and hence the approaching car can proceed at regular speed. The constant necessity of checking the speed of a car every time another car is passed at a corner, crossing or stopping point causes 10 much loss of time, and much of this could be avoided by giving a signal to the approaching car when speed was to be reduced.

Furthermore it often occurs at night that 15 there is a closely following car. In such cases the conductor can also throw his switch and the light signal will be given at the rear, thus notifying the following car that the one ahead is coming to a stop, either to discharge or take on a passenger, or through 20 the trolley leaving the wire. It is for this last reason that I employ a battery separate from the power supplied to operate the car, so that the signals are operative even when the car itself is without current for either 25 motive or lighting purposes.

I therefore provide for three distinct signaling operations, all independent of the

motive power of the car, viz., to the approaching car, to the passengers, and to a following car.

What I claim is:—

1. The combination with a car, visible and audible signals arranged at each end of the car, a source of electric current, normally broken circuits, each circuit including an 35 audible signal at one end of the car and a visible signal at the opposite end, means arranged at one end of the car for closing one of said circuits and means arranged at the opposite end for closing the other circuit. 40

2. The combination with a car, a bell arranged at each end of the car, a signal light arranged at each end of the car, a normally open switch arranged at each end of the car, a battery, an electric circuit including said 45 battery, the signal light and switch at the front end and the bell at the rear end of the car, and a second circuit including the battery, the switch and signal light at the rear end of the car and the bell at the forward 50 end of the car, as and for the purpose set forth.

In testimony whereof I affix my signature.
LEVY R. BOSTICK.
